UNITED STATES PATENT OFFICE.

NICHOLAS PIGNATARO, OF HILTON, NEW JERSEY.

ELECTRIC SIGNALING SYSTEM FOR RAILWAY-TRAINS.

1,266,150.

Specification of Letters Patent. Patented May 14, 1918.

Application filed January 16, 1914. Serial No. 812,335.

To all whom it may concern:

Be it known that I, NICHOLAS PIGNATARO, a citizen of the United States, residing at Hilton, in the county of Essex and State of New Jersey, have invented certain new and useful Improvements in Electric Signaling Systems for Railway-Trains; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in safety-appliances for railroads; and, the invention has reference, more particularly, to a novel electric system, acting automatically, and operating signals or indicating devices located upon the locomotives of trains operating in different blocks or sections of the railroad, the system being adapted to single or double tracks, for operating a signaling device from a train in a forward block to a train following rearwardly of the train in the forward block, and, furthermore, also providing an automatically operating signaling system that will notify the engineer or operator in a train of an open switch in the main line.

The invention has for its principal object to provide a novel and simply operating signaling system for railroads, and to provide a positive and reliable means in connection with the track and one or more locomotives for automatically sounding a signal or signals that will notify the engineer to proceed with caution or to entirely come to a stop.

The invention has for its further object to provide an electric danger-signaling system which is easy and inexpensive to manufacture and is easily installed, is thoroughly reliable and efficient in its use, and is readily applicable to block-systems, switches, drawbridges, and the like.

Other objects of this invention not at this time more particularly enumerated will be more fully understood from the follow-

ing detailed description of the present invention.

With the various objects of the present invention in view, the invention consists, primarily, in the novel train or locomotive-signaling system hereinafter set forth; and, the invention consists, furthermore, in the general arrangements and combinations of several automatically operating electrical instrumentalities and electric circuits, herein-after more fully described, illustrated in the accompanying drawings, and then embodied in the clauses of the claim which are appended to the said specification and which form an essential part of the same.

The invention is fully illustrated in the accompanying drawings, in which:—

Figures 1 and 1^a illustrate a diagrammatic representation of a locomotive or train-signaling system, showing one embodiment of the principles of the present invention, Fig. 1^a being a continuation of Fig. 1.

Fig. 2 is a plan view of one of a series of make and break appliances employed with the signaling system for completing an electrical circuit ahead of a locomotive or train and breaking the circuit in the rear of the locomotive or train; and Fig. 3 is a side elevation of the same.

Fig. 4 is a detail transverse vertical section of said appliance, said section being taken on line 4—4 in said Fig. 3, looking in the direction of the arrow x, and said view being made on an enlarged scale; and Fig. 5 is a similar sectional representation of the parts represented in said Fig. 4, but illustrating a pivoted trip-lever employed therewith in its released position.

Fig. 6 is a longitudinal vertical section of a portion of a railroad rail, provided with a receiving socket, and a contact-establishing element arranged in said receiving socket, said element being represented in its normal relation to the rail in the position when not establishing electrical contact; and Fig. 7 is a similar sectional representation of the same parts, the contact-establishing element being shown in the position when establishing a complete electric circuit.

Fig. 8 is a diagrammatic representation of

a portion of the train signaling system located at a switch or turn-out.

Fig. 9 is a diagrammatic view of a portion of the train signaling system, and a 5 make and break device located at the side of the railroad tracks, the make and break device being similar to the device illustrated in Figs. 2, 3, 4 and 5, but the device being provided in this instance with a semaphore 10 actuated by the pivoted trip-lever; and Fig. 10 is a detail face view of a portion of said make and break device, showing more particularly the location of the semaphore and a means of connection between the latter and 15 the pivoted trip-lever for actuating said semaphore.

Similar characters of reference are employed in all of the above described views, to indicate corresponding parts.

20 Referring now to the several figures of the drawings, the reference-characters 1 and 2 indicate the main rails of a railroad and upon which the trains may run in any usual manner, being drawn either by a 25 steam-locomotive or by electric motive power, and by the term train, as herein-after used, I include all kinds of railway-motors and vehicles either singly or attached.

30 Suitably arranged and secured between each pair of main rails 1 and 2 are other metal rail-like sections 3 and 4, laid parallel to the main rails, and said sections 3 and 4 being, respectively, interrupted by an arrangement of gaps or open spaces, as 5, 6, 35 and 7, between the ends of the said respective sections 3 and sections 4.

The reference-characters A and B indicate, diagrammatically, two trains running 40 upon the tracks 1 and 2, in figures 1 and 1^a, in the same direction.

Suitably mounted upon each train is a 45 battery 8, a switch 9, and a suitable signal-indicating device 10, which may be an electric bell. The reference-characters 11, 12, 13, and 14 indicate four contact-making 50 shoes, or other suitably-constructed contacts, which are suitably connected with each train A and B, and are in slidable contact, respectively, with the main rails 1 and 2, and the short rail-like sections 3 and 4. Each switch comprises a series of five binding posts 15, 16, 17, 18, and 19, and four contact posts 20, 21, 22, and 23. Pivottally 55 connected with the said binding posts 15, 16, 17, 18, and 19, are a series of five circuit-completing fingers 24, 25, 26, 27, and 28, with which is operatively connected an 60 actuating bar 29, which may be provided with a knob or finger-piece, for operating said fingers and for moving the respective fingers into circuit-completing contact with the various contact-posts 20, 21, 22, and 23.

At suitable intervals the rail 1 is provided 65 with receiving-sockets or openings,

as 30, 31, and 32, the rail 2 being provided with corresponding receiving sockets or openings, as 33, 34, and 35.

Near the gaps or breaks in the adjacent rail-like sections 3, the latter are respectively provided with correspondingly located receiving sockets or openings, as 36, 37, and 38, and, likewise, near the gaps or breaks in the adjacent rail-like sections 4, the latter are also respectively provided with correspondingly located receiving sockets or openings 39, 40 and 41.

In these various receiving sockets or openings are suitably disposed circuit making and breaking devices substantially of the 80 general construction represented in said Figs. 6 and 7 of the drawings.

The circuit-making and breaking devices each consist of a plate 42 suitably secured by means of screws 43, or otherwise, in the 85 said sockets of the rails 1 and 2 and the rail-sections 3 and 4, and flush therewith, and pivotally mounted in a suitable opening 44, with which each plate 42 is provided, is a compressible contact-element 45. Suitably 90 mounted upon one of said screws 43, between a pair of insulating disks 46, also arranged upon said screw, is a spring, as 47, which is suitably bent and has its end-portion 48 bearing upon a block 49 of insulating material and suitably secured to and projecting from the lower face of the contact-element 45. Under normal initial conditions, the spring 47 forces the said contact-element 45 in an upward direction 100 so that the end 50 of said element 45 will bear against the portion 51 of the plate 42 which acts as a stop, but allows the upper portion of the contact-element 45 to project slightly above the plane of the upper surface of the rail or rail-like section 105 with which the circuit-making and breaking device is employed. As diagrammatically shown, and as has been stated, the trains are provided with a series of four 110 circuit-establishing shoes or brushes, as 11, 12, 13, and 14, or other suitable devices, suspended from the train and respectively in sliding contact with the upper surfaces of the rails 1 and 2 and the rail-like sections 115 3 and 4. The result is that when a shoe or brush slides over a contact-element 45, the latter is depressed downwardly, as indicated in Fig. 7 of the drawings, in such a manner that the end-portion 50 of the element 45 is forced directly into contact with the end-portion 48 of the spring 47, as shown, to complete an electric circuit through a wire which is suitably attached to the screw 43 in contact with the spring 120 47, substantially as shown and for the purposes hereinafter more fully specified.

Located at suitable intervals at the sides of the rails 1 and 2, and in alignment transversely of said rails at the breaks between 125 130

the ends of the adjacent rail-like sections 3 and 4, are suitably constructed devices 52, each device being in the form of a combined make and break device and a resetting means 5 for the purposes hereinafter more fully specified.

This device is illustrated more particularly in Figs. 2, 3, 4 and 5 of the drawings, and the same comprises a suitable base, as 10 53, upon which is mounted a frame-work 54 carrying a pivoted lever 55 which is electrically controlled by an electro-magnet 56, in circuit, in the usual manner, with a pair of binding posts 57 and 58. Suitably mounted 15 upon said base 53 is a post or standard, as 59, carrying a plate 60. Upon this plate are three binding posts 61, 62 and 63, and a pair of electro-magnets 64, and their cores 65. Suitably connected with and extending 20 downwardly from a post 66 is a spring-supported contact-making shoe or bar, as 67, adapted at times to make contact with the ends of the cores 65. Connected with another post 68, and extending downwardly 25 therefrom, is a spring-bar 69, and pivotally mounted upon a pivot-post 70 is a contact making arm 71, one portion, as 72, of said arm being adapted to be brought slidably into holding engagement with a projection 30 73 with which the shoe or bar 67 is provided. The other portion or said arm 71 extends in an upward direction, as at 74, and is suitably weighted, as at 75, so that the said arm 71 assumes the position indicated in Fig. 5 35 of the drawings, when the portion 72 is disengaged from the projection 73 of the shoe or bar 67. An insulated wire 76 connects the binding post 63 in circuit with one terminal of the electro-magnet 64, the other 40 terminal of the magnet being connected by means of a wire 77 with a screw 78, and by means of the metal plate 60 electrical circuit is completed by means of the grounded post 79, and a spring-arm 80, through the shoe 45 or bar 67, arm 71, and pivot-post 70, which is insulated from said plate 60, and finally by means of another insulated wire 81, said pivot-post 70 to the binding post 62.

The post 68 is also connected electrically 50 by means of an insulated wire 82 with the binding post 61.

Having in the foregoing, in a general way, described the construction of the various instrumentalities employed, I will now endeavor to describe in connection with the 55 said instrumentalities the system of electric wiring between said instrumentalities and the rails 1 and 2 and rail-like sections 3 and 4, for establishing complete electric circuits 60 between two trains.

Referring now more particularly to Figs. 1 and 1^a of the drawings in which are diagrammatically represented two trains, the various above-described instrumentalities, 65 and various electric circuits, and also to

Figs. 2, 3, 4, 5, 6 and 7, in which are shown means for making and breaking the electric circuits, the reference-character 83 indicates a circuit-wire leading from the one terminal of each battery 8 to the binding post 18 70 of each device 9. Leading from the contact post 23, in Fig. 1^a, is a circuit-wire 84, said wire being connected with the sliding contact-shoe 11. Located between and connected with the other terminal of the battery 8 and the binding post 16 is a circuit wire 85, and leading from the contact-post 21 is a circuit wire 86, said wire being connected with the sliding contact shoe 13. Leading from the contact-post 22 is a circuit-wire 87 which is connected with the sliding contact-shoe 12, and leading from the contact-post 20 is another circuit wire 88 which is connected with the sliding contact-shoe 14. Leading from the binding 80 post 17 is a circuit wire 89 which is connected with one of the terminals of the electric bell 10, and leading from the binding post 19 is another circuit-wire 90 which is connected with the other terminal of the 90 electric bell 10. A third circuit wire 91 connects the binding post 15 with a portion of the circuit wire 90 and by means of this wire with the last-mentioned terminal of the electric bell 10. 95

Referring now to the circuit making and breaking devices 52, located adjacent to the rail 1, it will be seen, that the binding posts 57 have connected therewith, the circuit wires 92 leading to and suitably making 100 electrical connection, at the proper times, with the springs 48 and contact elements 45 located in the respective receiving sockets of the respective rail-like sections 3, and 93 are circuit wires connecting said rail-like sections 3 with the binding posts 61 of the respective circuit making and breaking devices 52 herein-above mentioned. 105

Leading from the binding posts 58 of each of said circuit making and breaking 110 devices, adjacent to the rail 1, are circuit wires 94 which are electrically connected with rail 1, and leading from the binding posts 63 of the same circuit making and breaking devices 52 are circuit wires 95 for 115 suitably making electrical connection, at the proper time, with the springs 47 and contact elements 45 located in the respective receiving sockets of the rail 1. The binding posts 62 of the said circuit-making and breaking 120 devices 52 are also electrically connected with the rail-like sections 3 by means of circuit wires 96.

Now, likewise, referring to the circuit-making and breaking devices located adjacent to the rail 2, it will be seen, that the binding posts 57 have connected therewith, the circuit wires 97 leading to and suitably making electrical connection, at the proper times, with the springs 47 and contact ele- 125

ments 45 located in the respective receiving sockets of the respective rail-like sections 4, and 98 are circuit wires connecting said rail-like sections 4 with the binding posts 61 of the respective circuit-making and breaking devices 52 thus located adjacent to the said rails 2. Leading from the binding posts 58 of each of said last-mentioned circuit-making and breaking devices 52, adjacent to the 10 rail 2, are circuit wires 99 which are electrically connected with the rail 2, and leading from the binding posts 63 of the same circuit making and breaking devices 52 are circuit wires 100 for suitably making electrical connection, at the proper times, with the springs 47 and contact elements 45 located in the respective receiving sockets of the rail 2. The binding posts 62 of the 15 said circuit-making and breaking devices 52 are also electrically connected with the said rail-like sections 4 by means of the circuit wires 101.

Referring now to Figs. 1 and 1^a, it will be noticed that the circuit-completing fingers 24, 25, 26, 27 and 28 in the alternating trains, in this case only two trains A and B being shown, are angularly set in opposite directions, so that in train A the fingers 24, 25, 26 and 27, respectively, contact with the 20 respective contact posts 20, 21, 22 and 23, of the device 9 in train A, and in train B the fingers 25, 26, 27 and 28, respectively, contact with the respective contact posts 20, 21, 22 and 23, of the device 9 in train B.

Having in the foregoing set forth the various circuit-wire connections, I will now briefly describe the manner of completing the electric circuits for setting into operation the electric bells indicating to the engineer of a train in one block or section, that there is still a train in the railway block or section into which he intends to pass, the bell in the danger-zone continuing to ring until the train ahead has passed out of its 40 block or section.

To this effect, I have represented in said Figs. 1 and 1^a of the drawings, in connection with the main rails 1 and 2, and the normally interrupted rail-like sections 3 and 4, 50 four railway blocks which I have indicated by the reference-letters C, C', C'', and C''', and in connection therewith I have shown train A as having passed into block C''' and train B into block C'.

In passing from the block C into block C', and subsequently into block C'' and C''', the sliding shoes 11, 12, 13 and 14 of the train A for an instant depress the contact elements 45 located in the respective recesses 60 of the respective rails and rail-like sections, as will be clearly evident. Immediately an electric circuit is established from the battery 8 in train A, through the circuit wire 83 to post 18, finger 27, contact-post 28, wire 84, shoe 11, contact element 45 in the socket

32 of the rail 1, the return-circuit being completed through the wire 95 to the binding post 63 of the device 52, located at D, and from the binding post 63 of said device, by means of the wire 76, the coils 64, the 70 wire 77 to grounded post 78, then by means of the plate 60 to grounded post 79, the member 80, the shoe 67, arm 72, pivot-post 70, and wire 81 to the binding post 62, to wire 96, the rail-like section 3 into the 75 sliding shoe 13, and wire 86 to the contact post 21 in the train A, the finger 25, binding 16, and finally by means of the wire 85 back to the battery 8 in said train A. Immediately upon the electro-magnets 64 thus becoming energized, and simultaneously with the sliding shoe 11 passing out of contact with the element 45 in the recess 32, the shoe 67 of the device at D is attracted by the magnetic cores 65, as shown in Fig. 5 of the 80 drawings, whereby the arm 72 becomes disengaged from its contact with the shoe 67, and engages with the spring-arm 69, as represented in said Fig. 5, and the completed electric circuit just described having accomplished its result, this circuit is once more interrupted or broken, and the gap 5 between the adjacent rail-like sections 3 is bridged electrically.

Train A now passing out of block C into block C' the sliding shoe 11 coming in contact with the depressible member 45 in the recess 31 of the rail 1, the same result takes place in connection with the device 52 located at D' in the block C', and so on as train 95 A passes from block to block. Now suppose that train B has entered from block C into the block C'. The electric current from the battery 8 in train A passes through the circuit wire 83 into post 18, finger 27, contact post 28, wire 84, and shoe 11 into the rail 1, the current then following the rail 1 until it reaches the sliding shoe 11 of train B. The current then passes from said last-mentioned shoe 11 of the train B, through the wire 84 to the contact post 28 in train B, finger 28, post 19, wire 90, to the electric bell 10 in train B, the circuit being completed from said bell 10 in train B, through the wire 89, post 17, finger 26, contact post 21, 105 all in train B, the wire 86 and shoe 13 of train B, through the rail-like section 3, and the wire 96 to the binding post 62 of the device 52 located at D'. 110

From the post 62, the current passes 120 through the wire 81, the pivot-post 70, the arm 72, the spring-bar 69, and the wire 82 to the post 61, as will be seen from an inspection of said Fig. 5, and through the circuit wire 93 into the rail-like section 3 located in the block C''. The electric current then passes through the rail-like section 3 in said block C'', through 96 to post 62 of the device 52 located at D'', completing the circuit through said device, in the manner above 125 130

described, and leaving at post 61, through the wire 93 to rail-like member 3 of block C'', into the shoe 13 and wire 86 of train A, into the contact post 21, finger 25, post 16, and finally by means of the wire 85 back to the battery 8 located in said train A. In this manner a complete electric circuit is established from train A now in block C'' to train B in block C', which keeps up the 10 ringing of the electric bell or other alarm or signaling device in said train B, until train A passes out of block C'' into the next block, whereby this circuit becomes automatically broken, and the bell in train B 15 ceases its ringing.

At the same time that train A has passed into block C'', it must follow that the previously operated mechanism of the device 52, located at D must be reset, that is the parts 20 must be moved from their operated positions indicated in Fig. 5 of the drawings, back to their normal initial positions represented in Fig. 4, and to again establish the break or gap between the rail-like members 3, between 25 blocks C and C'.

This is accomplished as follows:—

As soon as the sliding shoe 13 of train A depresses the contact element 45 located in the recess 36 of the rail-like section 3 of the 30 block C'', the current from the battery 8 in train A passes through the circuit wire 83 to post 18, finger 27 to contact post 23, wire 84 to sliding shoe 11, rail 1 to wire 94 and post 58 in the device 52 located at D. 35 From this post 58 the current passes into the electro-magnet 56, which becomes energized and attracts the pivoted lever 55, the upward movement of which engages the tilted arm 71, so as to bring its end 72 once 40 more into retained engagement with the projection 73 of the shoe 67, and the former electric circuit through the spring-arm 69 is again broken. From the electro-magnet 56 the current passes to the post 57, and thence 45 by means of the wire 92 to the depressible element 45 in the recess 36 of the rail-like section 3 in block C'', the return-circuit being completed through sliding shoe 13 of train A, in contact with said element 45, and 50 completed through wire 86, contact-post 21, finger 25, post 16, and finally through wire 85 to the battery 8 in said train A.

It will be clearly evident, that these various circuits are made and broken in the 55 manner hereinabove described as train A passes from block to block and is followed by train B.

Train B likewise makes and breaks electrical circuits and signals to a train following it, but in order that the instrumentalities may work properly without interfering with the proper workings of the instrumentalities operated from train A, the fingers 24, 25, 26, 27 and 28 are set, so as to 60 make contact with the different contact posts, 65

as indicated in Fig. 1^a, and as has been stated, the shoes 12 and 14 being used in connection with the rail 2 and the rail-like sections 4, and also with the various circuit-make and break devices 52 located adjacent to the rail 70 2, and the various circuit wires 97, 98, 99, 100 and 101 in the manner previously described. In all other respects the various operations for making and breaking the circuits is the same as that above stated, except that in connection with the poles of the device 9 in train B, when operating, the previously-mentioned circuit wire 91 is also used. 75

In Fig. 8 of the drawings is represented 80 diagrammatically an open switch running into a branch-road or a siding, and in connection therewith is shown an auxiliary electric circuit to be completed by the on-coming train, as it passes into the block in which 85 the switch is located.

Referring now to this Fig. 8, the reference-characters 1 and 2 indicate the main rails, and 3 and 4 the interrupted rail-like sections, as heretofore, the reference-characters 102 90 and 103, however, indicating the rails of the branch-road or siding, said rails 102 and 103 being connected by a circuit-wire 104, and the rail-like sections 3 and 4 being connected by a circuit-wire 105. The instrumentalities in the train, of course, are the same as those already described and are indicated by the same reference-characters herein-before employed. 95

The electric circuit from the battery 8 in 100 the train is made through wire 83, post 18, arm 27, contact-post 22, wire 88, sliding shoe 14, and rail-like section 4, the circuit being completed through wire 105 to rail-like section 3, shoe 13, wire 86, contact post 105 21, arm 26, and wire 89 to one of the terminals of the electric bell 10, the return-circuit being completed from the other terminal of the electric bell 10, through the wire 90, post 19, arm 29, contact post 23, 110 wire 84 and shoe 11 to the rail 1, into the rail 103 and circuit-wire 104 into rail 102, through rail 2 to the shoe 12, thence through the wire 87, to contact post 20, arm 25, post 16, and wire 85, finally to the other terminal of the battery 8. 115

As has been previously stated, the arms of the devices in the successive trains are set by the engineers so that they will point in opposite directions, alternately, in the successive trains, this being necessary because of the fact that while a signal is being received by train B from train A, a signal should also be sent from train B to a train following it. 120

Now, it may happen, when a train, as A, has run upon a side-track or onto a branch-road, that the angular relations of the arms 24 to 28 inclusive to the contact-posts in the succeeding trains should be changed, so that 130

the system will not become inoperative, in that case train B now assuming the roll of train A, the relative angular positions of the arms in the switch-devices 9 in the following trains being changed accordingly. To indicate to the engineers that such change must be made, the device 52 located in the main line, directly beyond the switch or point at which the side-track or branch-road leaves the main line is provided with a semaphore, as 106, swinging upon a pivot 107 carried by a post 108 extending in an upward direction from the plate 60. Pivotally connected with the semaphore 106 and the weighted part 75 of the device 52 is a link 109.

Now, suppose the semaphore points horizontally, which indicates to the engineer that the relative positions of the arms 24 to 28 inclusive should be changed from those shown in Fig. 9, so that arm 24 will contact with post 20, arm 25 with post 21, arm 26 with post 22, and arm 27 with post 23. In the device 52, thus employed, the circuit-wire 92 may be omitted, as unnecessary, and the rails 1 and 2 have receiving sockets, as 110 and 111, in each of which is pivotally mounted a contact-element 45, similar to the elements used with the device represented in Figs. 6 and 7 of the drawings, and previously described. Post 63 is connected in circuit with the device 45 in the socket 111 in rail 2 by a circuit-wire 112, the circuit being made through the shoe 12 to the device 9 in the train, and completed through the shoe 14 and rail-like section 4, and a circuit-wire 113 to the post 62 of the device 52, this circuit, however, being used only when train B is to set the semaphore horizontally. That train B will cause the semaphore 106 to drop as a signal to the engineer in a train following said train B, notifying the engineer in said following train that he is to change the positions of the arms 24 to 28 in his train, the sliding shoe 11 of train B in depressing the contact-element 45 located in the socket 110 in rail 1 completes an electric circuit through a wire 114 with the post 57 of the device 52, the circuit being completed through post 58, a wire 115 and the rail-like section 3 with the shoe 13, and finally completed with the instrument 9 in the same manner hereinbefore described, so that the semaphore is thus set in its proper indicating position for the next-following train, as will be clearly evident.

Of course I am fully aware that various changes may be made in the general arrangements and combinations of the various instrumentalities and electric circuits between said instrumentalities and the rails and rail-like members, as well as in the details of the constructions of the parts comprising the several instrumentalities, without

departing from the scope of the present invention as set forth in the foregoing specification and as defined in the clauses of the claims which are appended thereto. Hence, I do not limit my present invention to the exact arrangements and combinations of the various devices and parts, as well as the electric circuits between said devices and parts, as described in the said specification, nor do I confine myself to the exact details of the constructions of the various instrumentalities and their parts, as illustrated in the accompanying drawings.

I claim:

1. In an electric signaling system, in combination with the main rails and trains running upon said rails, sectional rails located between said main rails, said sectional rails being separated from each other so as to provide breaks at intervals, a source of electrical energy upon each train, an electric switch in circuit with said source of electrical energy, contact-elements carried at intervals by said main rails, contact-elements carried at corresponding intervals by the said rail-section, an electric signal carried upon each train, and sliding contacts also carried by the trains, said sliding contacts and electric signals being in circuit with the electric switches, contact-making and breaking devices located at intervals at the sides of the rails, each contact-making and breaking device being in circuit with a contact-element of the various main rails and with those of the rail-sections, so that when the proper circuit is established by the contacting of the sliding contacts with the contact-elements in the main rails and the rail-sections, said contact-making and breaking means acts to bridge the gaps between the several sectional rails two blocks to the rear of a train and also acts to open the same circuit when the train has progressed two blocks forward.

2. In an electric signaling system, in combination with the main rails and trains running upon said rails, sectional rails located between said main rails, said sectional rails being separated from each other so as to provide breaks at intervals, a source of electrical energy upon each train, an electric switch upon each train, in circuit with said main source of electrical energy, contact-elements carried at intervals by said rails, contact-elements carried at corresponding intervals by said rail-sections, and sliding contact-means carried by each train, circuit-wires leading from the respective switches to the respective contact-means, to bring the various members into electric circuit, electric bells and circuit-wires leading from the respective bells to the respective switches, contact-making and breaking means located at intervals at the sides of the rails, each contact-making and breaking device being in

circuit with a contact-element of the various main rails and with those of the rail-sections, so that when the proper circuit is established by the contacting of the sliding 5 contacts with the contact-elements in the main rails and the rail-sections, said contact-making and breaking means acts to bridge the gaps between the several sectional rails two blocks to the rear of a train and also acts to open the same 10 circuit when the train has progressed two blocks forward.

3. In an electric signaling system, in combination with the main rails and trains running upon said rails, sectional rails located 15 between said main rails, said sectional rails being separated from each other so as to provide breaks at intervals, a source of electrical energy upon each train, an electric switch upon each train in circuit with said main 20 source of electrical energy, contact-elements carried at intervals by said rails, contact-elements carried at corresponding intervals by said rail-sections, and sliding rails, contact-making shoes carried by each train, circuit-wires leading from the respective switches to the respective contact-making shoes, to bring the various members into 25 electric circuit, electric bells and circuit switches, contact-making and breaking means located at intervals at the sides of the rails, each contact-making and breaking device being in circuit with a contact-element of the various main rails and with those of the rail-sections, so that when the 30 proper circuit is established by the contacting of the sliding contacts with the contact-elements in the main rails and the rail-sections, said contact-making and breaking means acts to bridge the gaps between the 35 several sectional rails two blocks to the rear of a train and also acts to open the same circuit when the train has progressed two blocks forward.

4. In an electric signaling system, in combination with the main rails and trains running upon said rails, a series of gapped sectional rails located between said main rails, a source of electrical energy upon each train, an electric switch upon each train in circuit with said main source of electrical energy, contact-elements carried at intervals by said rails, contact-elements carried at corresponding intervals by said rail-sections, and sliding contact-making shoes carried by 55 each train, circuit-wires leading from the respective switches to the respective contact-making shoes, to bring the various members into electric circuit, electric bells and circuit-wires leading from the respective bells to 60 the respective switches, each contact-making and breaking device being in circuit with a contact-element of the various main rails and with those of the rail-sections, so that when the proper circuit is established by the contacting of the sliding contacts with the con- 65

tact-elements in the main rails and the rail-sections, said contact-making and breaking means acts to bridge the gaps between the several sectional rails two blocks to the rear of a train and also acts to open the same circuit when the train has progressed two blocks forward. 70

5. In an electric signaling system, in combination with the main rails and trains running upon said rails, sectional rails located 75 between said main rails, said sectional rails being separated from each other so as to provide breaks at intervals, said main rails and said rail-sections being provided at intervals with receiving-sockets, a source of 80 electrical energy upon each train, an electric switch upon each train in circuit with said main source of electrical energy, contact-elements movably disposed in the sockets of said main rails and rail-sections, contact- 85 means carried by each train, circuit-wires leading from the respective switches to the respective contact-means to bring the various members into electric circuit, danger-signaling devices and circuit-wires leading 90 from the respective signaling devices to the respective switches, contact-making and breaking means located at intervals at the sides of the rails, each contact-making and breaking device being in circuit with a contact-element of the various main rails and with those of the rail-sections, so that when the proper circuit is established by the contacting of the sliding contacts with the contact-elements in the main rails and the rail-sections, said contact-making and breaking means acts to bridge the gaps between the several sectional rails two blocks to the rear of a train and also acts to open the same circuit when the train has pro- 95 gressed two blocks forward. 100

6. In an electric signaling system, in combination with the main rails and trains running upon said rails, a series of gapped sectional rails located between said rails, said 110 rails and said rail sections being provided at intervals with receiving sockets, a source of electrical energy upon each train in circuit with said main source of electrical energy, an electric switch upon each train, 115 contact-elements movably disposed in the sockets of said main rails and rail-sections, contact-means carried by each train, circuit-wires leading from the respective switches to the respective contact-means to bring the 120 various members into electric circuit, danger-signaling devices and circuit-wires leading from the respective signaling devices to the respective switches, contact-making and breaking means located at intervals at the 125 sides of the rails, each contact-making and breaking device being in circuit with a contact-element of the various main rails and with those of the rail-sections, so that when the proper circuit is established by the con- 130

tacting of the sliding contacts with the contact-elements in the main rails and the rail-sections, said contact-making and breaking means acts to bridge the gaps between the several sectional rails two blocks to the rear of a train and also acts to open the same circuit when the train has progressed two blocks forward.

7. In an electric signaling system, in combination with the main rails and trains running upon said rails, section rails located between said main rails, said sectional rails being separated from each other so as to provide breaks at intervals, said main rails and said rail-sections being provided at intervals with receiving sockets, a source of electrical energy upon each train, an electric switch upon each train in circuit with said main source of electrical energy, contact elements movably disposed in the sockets of said main rails and rail sections, contact-means carried by each train, circuit-wires leading from the respective switches to the respective contact-means to bring the various members into electric circuit, electric bells and circuit-wires leading from the respective bells to the respective switches, contact-making and breaking means located at intervals at the sides of the rails, each contact-making and breaking device being in circuit with a contact-element of the various main rails and with those of the rail-sections, so that when the proper circuit is established by the contacting of the sliding contacts with the contact-elements in the main rails and the rail-sections, said contact-making and breaking means acts to bridge the gaps between the several sectional rails two blocks to the rear of a train and also acts to open the same circuit when the train has progressed two blocks forward.

8. In an electric signaling system, in combination with the main rails and train running upon said rails, a series of gapped sectional rails located between said rails, said rails and said rail-sections being provided at intervals with receiving sockets, a source of electrical energy upon each train, an electric switch upon each train in circuit with said main source of electrical energy, contact-elements movably disposed in the sockets of said main rails and rail sections, contact-means carried by each train, circuit-wires leading from the respective switches to the respective-contact means to bring the various members into electric circuit, electric bells and circuit-wires leading from the respective bells to the respective switches, contact-making and breaking devices located at intervals at the sides of the rails, each contact-making and breaking device being in circuit with a contact-element of the various main rails and with those of the rail-sections, so that when the proper circuit is established by the contacting of the sliding contacts with the

contact-elements in the main rails and the rail-sections, said contact-making and breaking means acts to bridge the gaps between the several sectional rails two blocks to the rear of a train and also acts to open the same circuit when the train has progressed two blocks forward.

9. In an electric signaling system, in combination with the main rails and trains running upon said rails, sectional rails located between said main rails, said sectional rails being separated from each other so as to provide breaks at intervals, said main rails and said rail-sections being provided at intervals with receiving sockets, a source of electrical energy upon each train, an electric switch upon each train in circuit with said main source of electrical energy, contact-elements movably disposed in the sockets of said main rails and rail-sections, contact-making shoes carried by each train, circuit-wires leading from the respective switches to the respective contact-making shoes, danger-signaling devices and circuit-wires leading from the respective signaling devices to the respective switches, contact-making and breaking means located at intervals at the sides of the rails, each contact-making and breaking device being in circuit with a contact-element of the various main rails and with those of the rail-sections, so that when the proper circuit is established by the contacting of the sliding contacts with the contact-elements in the main rails and the rail-sections, said contact-making and breaking means acts to bridge the gaps between the several sectional rails two blocks to the rear of a train and also acts to open the same circuit when the train has progressed two blocks forward.

10. In an electric signaling system, in combination with the main rails and trains running upon said rails, a series of gapped sectional rails located between said rails, said rails and said rail-sections being provided at intervals with receiving sockets, a source of electrical energy upon each train, an electric switch upon each train in circuit with said main source of electrical energy, contact-elements movably disposed in the sockets of said main rails and rail-sections, contact-making shoes carried by each train, circuit-wires leading from the respective switches to the respective contact-making shoes to bring the various members into electric circuit, danger-signaling devices and circuit-wires leading from the respective signaling devices to the respective switches, contact-making and breaking means located at intervals at the sides of the rails, each contact-making and breaking device being in circuit with a contact-element of the various main rails and with those of the rail-sections, so that when the proper circuit is established by the contacting of the sliding contacts with the

the contact-elements in the main rails and the rail-sections, said contact-making and breaking means acts to bridge the gaps between the several sectional rails two blocks to the 5 rear of a train and also acts to open the same circuit when the train has progressed two blocks forward.

In testimony, that I claim the invention set forth above I have hereunto set my hand this 9th day of January, 1914.

NICHOLAS PIGNATARO.
